[57] **CLAIM**

The ornamental design for a trailer hitch cover, as shown and described.

DESCRIPTION

FIG. 1 is a perspective view of a trailer hitch cover showing my new design;

FIG. 2 is a top plan view thereof;

FIG. 3 is a front elevational view thereof;

FIG. 4 is a right side elevational view thereof;

FIG. 5 is a bottom plan view thereof; and,

FIG. 6 is a rear elevational view thereof.

The broken line showing of environment is for illustrative purposes only and forms no part of the claimed design.
